UNITED STATES PATENT OFFICE.

JAMES W. BONTA, OF PHILADELPHIA, PENNSYLVANIA.

TELEPHONE-TRANSMITTER.

SPECIFICATION forming part of Letters Patent No. 352,179, dated November 9, 1886.

Application filed March 11, 1886. Serial No. 194,804. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

Figure 1 is a sectional elevation of a telephonic transmitter embodying my improvements in the most desirable form. Fig. 2 is a like view of same in its simplest form. Fig. 3 is a like view of modification of same, and Fig. 4 is a detail elevation of loose ball or electrode and supporting plate or table.

My invention has relation to telephonic transmitters of the form having a loose ball or electrode, an adjustable carbon or other table or block for supporting the ball, and mechanism for elevating, lowering, and tilting the table to vary the initial contact-pressure of the electrodes; and it has for its object to dispense with the elevating, lowering, and tilting ball or loose electrode holder or plate and substitute therefor a fixed plate so constructed and having tension devices, whereby the initial contact-pressure between the electrodes is varied as desired without tilting or elevating and depressing said plate, as has heretofore been done.

My invention accordingly consists of the combination, construction, and arrangement of parts, as hereinafter described and claimed.

A represents a transmitter case or box having a removable front, *a*, provided with a mouth-piece, *a'*, and to which is secured a diaphragm, *B*, the frame of which has inwardly-projecting top and bottom standards or bars, *b'* and *b*, respectively. The diaphragm, if it is an iron plate, is preferably provided with a fixed carbon electrode, *b*, as shown in Fig. 1; but if a carbon plate the said electrode is dispensed with, as shown in Fig. 2, in which case the diaphragm may be hinged to the box-front, as illustrated. The hinging of this carbon diaphragm to the box I do not herein claim, as it is reserved for the subject of a future application.

To the outer end of standard *b'* is pivoted a depending bar, *C*, having a knee or bend, as shown at *c*. To the upper part of the bar *C*,

and on its side next to the diaphragm, is fastened a thin strip or plate, *D*, to the lower end of which is secured a block, *E*, of carbon or analogous or other suitable material, having in its front and top sides a concavity or oval or other similar recess or chamber, *e*, for the reception of a loose carbon ball or electrode, *F*, which contacts with electrode *b* or the diaphragm, as shown. The strip or plate *D* is preferably slightly elastic, and, if desired, may be adjustable on bar *C* by means of the set-screw *d*, passing through a slot, *d'*, in said plate. The lower standard, *b'*, is provided with an end or lip, *b''*, through which passes a set-screw, *b'*, for impingement against lower end of bar *C*, and to the bar is secured a spring, *G*, the free end *g* of which abuts against said lip or end *b''*. The spring is so arranged that its action or force is toward the diaphragm. As the screw *b'* therefore is adjusted more or less the ball *F* correspondingly moves, rolls, or rides up and down the inclined or curved sides *e'* of the recess or chamber *e*, to assume its position relative to such adjustment for varying its contact-pressure with the diaphragm or its electrodes, and this adjustment or variation of contact-pressure is consequently made without moving the block or plate *E*. 80

If desired, the tension or adjusting devices for block *E* may be dispensed with, as shown in Fig. 2, and instead of fastening the strip or plate *D* to the bar *C* or to the case *A*, it may be pivoted to a swiveled connection, *h*, on the end 85 of a screw, *h'*, as illustrated in Fig. 3, so that the block can be raised or lowered to place the ball in the center of the diaphragm. In this case a fork or guide engages with the block to keep it from turning, and the contact-pressure 90 of the electrodes is constant, as it also is when the construction shown in Fig. 3 is used.

Any suitable inductorium, *I*, may be used, the primary one of which includes the diaphragm *B* or its electrode *b*, the ball *F*, plate 95 or block *E*, and battery *3*, and the secondary forms part of the line.

I do not broadly claim in this application the means for vertically adjusting the support for the loose electrode with varying the inclination of the support, as that forms the subject-matter of a separate application filed on even date with this and numbered 194,801.

What I claim is—

1. In a telephonic transmitter, a diaphragm, a loose ball or electrode, and a block or plate having a curved or oval recess or chamber, *e*, substantially as shown and described.

5. 2. In a telephonic transmitter, a diaphragm, a loose ball or electrode, a block, *E*, having curved or oval chambers *e'*, and devices for raising and lowering block *E*, substantially as shown and described.

10. 3. In a telephonic transmitter, a diaphragm, a loose ball or electrode, a block or table, *E*, having curved or oval chamber *e'*, and contact pressure tension devices for the electrodes, substantially as shown and described.

4. The combination of diaphragm *B*, loose ball or electrode *F*, block *E*, having chamber *e*, pivoted bar *C*, supporting-block *E*, spring *G*, and set-screw *b'*, substantially as shown and described.

In testimony whereof I affix my signature in presence of two witnesses.

JAMES W. BONTA.
